Attorney

UNITED STATES PATENT OFFICE.

CHARLES P. SWICK, OF WATERBURY, CONNECTICUT, ASSIGNEE TO AMERICAN RING COMPANY, OF WATERBURY, CONNECTICUT, A CORPORATION OF CONNECTICUT.

SHADE HOLDER.

Application filed May 19, 1924. Serial No. 714,414.

To all whom it may concern:

Be it known that I, CHARLES P. SWICK, a citizen of the United States, residing at Waterbury, in the county of New Haven and State of Connecticut, have invented certain new and useful Improvements in Shade Holders, of which the following is a specification, reference being had thereto in to the accompanying drawings.

10 This invention relates to a shade holder to be attached to an electrical lamp socket or the like,

15 It is the object of this invention, among other things, to provide a simple and inexpensive shade holder that may be readily attached and detached to a lamp socket and will have a firm and fixed connection therewith, and will, with the conventional form of lamp socket, hold the parts there-
20 of together against accidental displacement or separation.

25 To these, and other ends, my invention consists in the shade holder, having cer-
tain details of construction and combina-
tions of parts, as will be hereinafter de-
scribed and more particularly pointed out
in the claims.

30 Referring to the drawings, in which like numerals of reference designate like parts in the several figures:

Figure 1 is an elevation of my improved shade holder, illustrated as applied to an electric lamp socket;

35 Figure 2 is an enlarged sectional view of the ring member thereof and a portion of the lamp socket; and

Figure 3 is an enlarged sectional view of the ring member, taken generally upon line 3—3 of Figure 1.

40 As shown herein the improved shade holder is constructed preferably with a ring member 10, head member 11 and arms 12, which may be secured in any preferred manner. This form of shade holder, how-
45 ever, is illustrated merely for the purpose of showing one type thereof. Any other form, type or structure of shade holder or similar mechanism may be applied to the ring 10 within my invention, as may be desirable, for instance, if the lamp socket is to occupy a substantially horizontal rather than a vertical position.

50 The lamp socket illustrated in the drawings is of the ordinary or conventional type, having a body member 13, with a reduced

portion 17 and a shoulder 18, and a cap member 14 having an enlarged collar 15 at one end.

These two members are usually secured together by projecting the body member 13 60 into the open end of the cap member 14 at the collar 15.

A push plug 16 provides the means to turn on and off the current in the lamp socket. A turn button may be substituted 65 for the push plug, as is usual.

The ring 10 has an inwardly turned flange 19 at one end and an enlarged collar 20 at the other end, which is formed with a plurality of spring fingers 26, sep- 70 arated by the longitudinal slots 21. The outer ends of each of these fingers has an inwardly turned lip 22 and an outwardly flaring tip 23.

The flange 19 is preferably but not neces- 75 sarily curved to conform with the curvature of the shoulder 18.

This ring 10 is assembled with the lamp socket by passing the body member 13 of the latter therethrough, during which the spring fingers 26 yield sufficiently to permit the lips 22 to pass over the collar 15 and then snap over the end wall 24 thereof. When so positioned the flange 19 is in contact with the shoulder 18. This ring is thus 85 rigidly held by the lamp socket at both ends thereof and the two portions of the sockets are so gripped against movement therebetween as to prevent separation there-
90 of.

In opposite sides of the ring member 10 are the slots 25 that permit the ends of the push plug 16 to pass therethrough during the assembly of the ring with the lamp socket.

95 What I claim as new and desire to secure by Letters Patent, is:—

1. In combination with a lamp socket, having a body member and cap member; a one piece device of the character described 100 in ring form, one end of which engages a shoulder upon the body member and the other end of which engages a shoulder upon the cap member and holds the members against endwise movement relatively to each other.

2. In combination with a lamp socket having a body member and a cap member having a collar thereon, the body member having a reduced portion with a shoulder 110

- connecting the adjacent larger portion; a one piece device of the character described in ring form with an inwardly turned flange at one end which engages the said shoulder when the ring is assembled with the lamp socket, and spring fingers at the opposite end of the ring which engage the face of said collar opposite to that of said shoulder.
- 5 10 3. A shade holder having a ring with a collar at one end provided with a plurality of slots that are open at one end with the end portions of the collar between the slots turned inwardly to provide lip portions, and the opposite end of the ring 15 having an inwardly turned flange, whereby when assembled with a lamp socket one wall of the collar and said lip portions engage oppositely disposed walls of a collar upon the lamp socket and the inwardly 20 turned flange will engage a shoulder upon the lamp socket and hold the members of the lamp socket against endwise movement relatively to each other.
- 10 In testimony whereof, I have hereunto 25 affixed my signature.

CHARLES P. SWICK.
